BARK-REMOVING CUTTER RECIPROCABLE
OVER STEP-BY-STEP ROTATABLE LOG

Price Wilson, Lexington, N. C., assignor of one-half to Linwood Manufacturing Co., Linwood, N. C., a corporation of North Carolina

Application April 16, 1951, Serial No. 221,171

10 Claims. (Cl. 144—208)

1
This invention relates to woodworking machinery and more especially to an improved machine for peeling logs for removing the bark therefrom preparatory to the logs being turned down to form veneer sheets therefrom.

Heretofore, in order to prepare a log for veneer manufacturing machines and the like, it has been necessary to subject the log to a steam bath for a relatively long period whereupon the bark would usually fall off, or a large number of operators has been required to remove the bark from the logs with axes or draw knives so as to properly condition the logs for the veneer cutting machines. This has not only been a time consuming task but has required a relatively large number of operators and has often resulted in the surface of the logs being rather severely indented by the draw knives or axes used in performing this operation with the result that the first layer of veneer removed from the log would have to be discarded.

It is, therefore, an object of this invention to provide a machine for removing bark from logs whether or not the logs have been subjected to steam, which machine may be easily and economically constructed and which may be operated by only one or two operators thus rendering the bark removing operation relatively economical and simple.

It is another object of this invention to provide a log peeling machine having means for supporting and imparting rotation to a substantially cylindrically-shaped workpiece such as a log, in a step-by-step manner, and also having a vertically movable and horizontally movable carriage disposed above the log so positioned, and rotatable cutting means carried by the carriage whereby, upon a log being positioned on the supporting means therefor, the carriage may be lowered to where the cutting means carried thereby will remove a predetermined amount of stock from the periphery of the log as the carriage is subsequently moved longitudinally of said log in a reciprocatory manner. The means for imparting step-by-step rotation to the log only operates to impart a step thereto following each bark removing pass of the carriage.

It is still another object of this invention to provide a machine of the type described that can also handle tapered logs, since means are provided for tilting the supporting means for the log, thereby tilting the longitudinal axis of the log and presenting the upper surface of the log in substantially parallel relation to the path of travel of the carriage and the cutting means.

2
mounted thereon, and thus insuring removal of the bark from the entire length of the log.

More specifically, it is an object of this invention to provide a log peeling machine comprising a fixed frame having a tiltable frame thereon and means associated with the tiltable frame for supporting a log or the like, and said means for supporting the log also being provided with means for imparting manually controlled step-by-step rotation to the log. The stationary frame also carries a vertically movable frame or elevator which is manually controlled as to its vertical position and on which a manually controlled horizontally movable carriage is provided, this carriage having a cutting means depending therefrom and mounting means for imparting rotation to the cutting means to thus remove the bark from the upper surface of the log upon each bark removing pass of the carriage, the log being rotated a step following each alternate reciprocation of the carriage to the initial position of its operating cycle.

Some of the objects of the invention having been stated, other objects will appear as the description proceeds when taken in connection with the accompanying drawings, in which—

Figure 1 is a side elevation of the improved log peeling machine;

Figure 2 is an enlarged front end elevation of the machine looking at the right-hand side of Figure 1;

Figure 3 is an enlarged rear end elevation of the machine looking at the left-hand side of Figure 1, some of the parts in the background thereof being omitted for purposes of clarity;

Figure 4 is a sectional plan view of the machine and is taken substantially along the line 4—4 in Figure 1;

Figure 5 is another sectional plan view of the machine and is taken along the line 5—5 in Figure 1;

Figure 6 is an enlarged vertical sectional view taken substantially along the line 6—6 in Figure 1;

Figure 7 is an enlarged fragmentary vertical sectional view taken substantially along the line 7—7 of Figure 6;

Figure 8 is a schematic illustration showing the electrical connections between the various electric motors associated with the present machine and the switches for controlling the same.

Referring more specifically to the drawings, the numeral 10 broadly designates a stationary or fixed frame wherein the various parts thereof, to be presently described, may be welded or

otherwise suitably secured to each other. Hereinafter, the various frame members which are referred to as I-beams, channel bars, and angle bars, may be of any desired shape to produce the required results.

The frame 10 comprises transversely spaced longitudinally extending frame members 11 and 12, opposed ends of which are joined by transverse frame members 13 and 14 which form the base of the machine. Opposed ends of the transverse frame members 13 and 14 support the lower ends of respective I-beams 15, 16 and 17, 18 which extend upwardly and support the opposed ends of respective pairs of closely spaced transversely extending channel bars 20, 21 and 22, 23. The flanges of the channel bars 20, 21 and 22, 23 preferably face inwardly towards each other and their proximate edges are spaced from each other for purposes to be later described.

The floor or surface F on which the frame 10 rests (see Fig. 6) should be disposed at a lower elevation than the adjacent floor or surface which is indicated at F-1 so that the surface F-1 may be at substantially the same level as the upper surfaces of a pair of transversely spaced longitudinally extending frame members 25, 26 which comprise a tiltable log supporting frame or table designated broadly as 27. The frame members 25, 26 are shown in the form of I-beams, and opposed ends thereof are suitably secured, as by welding to the opposed ends of respective channel bars 30, 31. The lower surfaces of the longitudinally extending frame members 25, 26 are also bridged by transversely extending frame members 32 to 38, inclusive, which are spaced from each other longitudinally of the frame members 25, 26 and are suitably secured thereto as by welding. The members 32, 33, 34, are shown in the form of angle bars, 37 and 38 are shown in the form of channel bars and members 35, 36 are shown in the form of I-beams (Figure 1).

The tiltable frame 27 is supported for rocking movement or oscillation on the transversely spaced longitudinally extending frame members 11 and 12. In this instance, bearing blocks 42, 43 are suitably secured to the lower surfaces of the respective longitudinally extending frame members 25, 26, as by screws 44. A pivot shaft 45 is fixed in the blocks 42 and 43 and is oscillatably mounted in bearing blocks 46 and 47 which are suitably secured, as by welding, to the upper surfaces of the longitudinally extending frame members 11, 12 of the fixed frame 10. The log supporting frame 27 is supported for oscillation for purposes to be presently described.

The log supporting frame 27 is held in the desired attitude relative to the longitudinally extending frame members 11 and 12 by a threaded shaft 50 (Figure 2) which threadably penetrates the upper horizontal flange of the transverse channel bar 32 and which extends from a suitable gear reduction unit 51 driven by an electric motor 52. The gear reduction unit 51 and the electric motor 52 are of usual construction and a detailed description thereof is deemed unnecessary. The electric motor 52 is a reversing motor and it will be observed in Figures 4 and 8 that this reversing motor 52 has wires 53 to 56, inclusive, extending therefrom. The point to which these wires 53 to 56, inclusive, extend will be later described.

The gear reduction unit 51 and the associated electric motor 52 are suitably secured to the upper surfaces of a pair of longitudinally spaced slats or bars 60 and 61, downwardly between which the shaft 50 extends. Opposed ends of the bars

60 and 61 are suitably secured, as by welding, to vertically disposed support plates 63 and 64 which extend downwardly and are suitably secured, as by welding, to the longitudinally extending frame members 11 and 12, respectively, as well as being secured to the inner surfaces of the vertically disposed I-beams 15 and 16, respectively. The electric motor 52 is controlled by a manually operable double pole snap switch 65 (Figures 1, 5 and 8) which is provided with circularly spaced contact members 65a to 65d, inclusive. The switch 65 (Figure 8) is also provided with an oscillatable bus bar 66 which, at times, is adapted to effect the flow of electrical energy between the contacts 65a and 65d and at other times to effect a circuit between contacts 65b and 65c. The wires 53 and 54 from the electric motor 52 are connected to the respective contact members 65a and 65b and the contact members 65c and 65d have respective wires 67 and 68 connected thereto which extend downwardly in Figure 8 and are connected to respective lead wires 72 and 73. The wires 55 and 56 from the electric motor 52 are connected intermediate the ends of the wires 68 and 67, respectively. The lead wires 72 and 73 have a master switch 76 interposed therein and extend from a suitable connector 75 which is adapted to be connected or plugged into a suitable source of electrical energy, not shown.

Upon the bus bar 66 effecting a circuit between the contacts 65a and 65d in the switch 65, the threaded shaft 50 (Figure 2) will rotate in one direction so as to elevate the corresponding end of the log supporting frame 27. It is obvious that upon the bus bar 66 being positioned so as to effect a circuit between the contacts 65b and 65c, the shaft 50 would be caused to rotate in the opposite direction to lower the log supporting frame 27.

Referring to Figures 1, 2 and 4, it will be observed that a gear reduction reversing motor 80 is suitably secured, as by screws 81, to the upper surfaces of the spaced transverse frame members 33 and 34. This motor 80 has wires 82 to 85, inclusive, extending therefrom, the wires 82 and 83 being connected to respective spaced contact members 87a and 87b of a double pole snap switch 87 (Figures 5 and 8) which also has spaced contact members 87c and 87d thereon. The switch 87 also has a manually movable bus bar 88 thereon which, at times, will effect a circuit between the contacts 87b and 87d and which will, at other times, effect a circuit between the contact members 87a and 87c. Wires 91 and 92 are connected to the respective contact members 87c and 87d and their other ends are connected to the respective lead wires 72 and 73. The wires 84 and 85 are connected intermediate the ends of the respective wires 91 and 92.

Referring again to Figure 4, it will be observed that the gear reduction motor 80 has a shaft 94 extending therefrom on which a sprocket wheel 95 is fixedly mounted. This sprocket wheel 95 has a sprocket chain 96 mounted thereon which is also mounted on a sprocket wheel 97 fixedly mounted on a shaft 100. The shaft 100 extends longitudinally of and in parallel relation to the frame member 26 of the log supporting frame 27 and is rotatably mounted in a plurality of bearing blocks 101, there being one of each of the bearing blocks 101 suitably secured, as by screws 102, to the upper surface of each of the transverse frame members 34 to 38, inclusive.

The shaft 100 has a pair of traction wheels 104 and 105 fixedly mounted thereon which are shown

in the form of sprocket wheels. These traction wheels 104 and 105 are disposed between the bearing blocks 101 which are mounted on the respective transverse frame members 35, 36 and 37, 38.

A pair of idler traction wheels 106 and 107, which are also shown in the form of sprocket wheels are fixedly mounted on a longitudinally extending shaft 110 disposed in horizontally spaced relation to the shaft 100. The shaft 110 is rotatably mounted in bearing blocks 111, one of each of which is suitably secured, as by screws 112, to the upper surface of the corresponding transverse frame members 36 to 38, inclusive.

The log or substantially cylindrically-shaped workpiece is indicated at W and may be rolled from the surface F-1 (Figure 6) over the corresponding longitudinally extending frame member 25 or 26 of the log supporting frame 27 to be supported by and between the traction wheels 104 and 106 and 105 and 107.

It is thus seen that, upon the bus bar 88 being positioned so as to effect a circuit between the contacts 87b and 87d, the shaft 94 of the motor 80 will rotate in one direction so as to impart rotation to the log or workpiece W in one direction, say, a counter-clockwise direction in Figure 6, and, upon the bus bar 88 being positioned so as to effect a circuit between the contact members 87a and 87c, the shaft 94 will rotate in the opposite direction so as to cause the traction wheels 104 to 107, inclusive, to rotate in a counter-clockwise direction in Figure 6 and to, in turn, cause the workpiece W to rotate in a clockwise direction.

It is evident that, if the workpiece W is of smaller diameter at one end thereof than it is at its other end, the upper surface thereof should be disposed in a substantially level plane throughout its length and, therefore, the reversing motor 52 may be energized in the manner heretofore described so as to raise or lower the right-hand end of the log supporting frame 27 in Figure 1 to accordingly cause the upper surface of the workpiece W to be disposed in a substantially horizontal plane.

Vertically movable frame and cutting device carriage

A vertically movable frame or elevator designated broadly at 120 is mounted for vertical movement relative to the fixed or stationary frame 10. This vertically movable frame 120 has a pair of transversely spaced longitudinally extending frame members 121 and 122 which are shown in the form of I-beams (Figures 1, 3, 5 and 6). The lower horizontal flanges of these I-beams 121 and 122 serve as trackways for a wheeled carriage designated broadly at 124 and which will be later described in detail.

Opposed ends of the longitudinally extending frame members 121 and 122 of the vertically movable frame 120 rest upon and are suitably secured to transverse bars 125 and 126. Opposed ends of the bars 125 and 126 are suitably secured, as by welding, to the proximate faces of respective vertically disposed channel bars 127 and 128 and 131 and 132. The flanges of the channel bars 127, 128, 131 and 132 face inwardly and the upper ends of the channels 127, 128 and 131, 132 are suitably secured, as by welding, to opposed ends of respective transverse frame members 133 and 134, which are shown in the form of channel bars. The lower ends of the channel bars 127, 128 and 131, 132 have opposed ends of respective frame members 135, 136 (Fig-

ures 3 and 6) suitably secured thereto as by welding, these frame members 135, 136 also being shown in the form of channel bars.

Since the upper channel bars 133, 134 support the elevator 120, they are reenforced by respective suitable diagonally disposed members 140, 141 and 142, 143, the upper ends of which are welded to and spaced adjacent the medial portions of the respective channel bars 133, 134 and which extend downwardly in diverging relation and the lower ends of which are welded intermediate the ends of the respective vertically disposed channel bars 127, 128 and 131, 132.

The lower ends of respective cables 145, 146 are suitably secured to the medial portions of the transversely extending channel bars 133, 134 (Figures 3 and 6) by any suitable means, such as eye bolts 147. These cables 145, 146 extend upwardly and pass between the respective pairs of transverse channel bars 20, 21 and 22, 23 and then over suitable rollers or grooved wheels 150, 151, respectively. The grooved wheels 150, 151 are rotatably mounted on respective stub shafts 152, 153, opposed ends of which are fixedly mounted in longitudinally extending transversely spaced channel bars 154, 155 (Figures 1, 2 and 3).

The longitudinally extending channel bars 154, 155 are suitably secured, as by welding, to the upper surfaces of the channel bars 20 to 23, inclusive, and it will be observed in Figure 1 that the front or right-hand ends of the channel bars 154, 155 extend substantially beyond the transverse channel bar 20. The cables 145, 146 extend forwardly between the channel bars 154, 155 and pass over respective grooved pulleys or wheels 156, 157 and then extend downwardly (Figure 1) and are suitably secured to a flanged reel or drum 160.

The reel 160 is rotatably mounted in bearing stands 161, 162 which are suitably secured to the upper surface of a support plate 163, which extends forwardly from the stationary frame 10 as shown in Figures 1 and 5. The rear or inner end of the support plate 163 is suitably secured, as by welding, to the upper surface of a transverse channel bar 165, opposed ends of which are suitably secured, as by welding, to bars 166, 167 which extend inwardly and are welded to the outer surfaces of the respective vertically disposed frame members 15, 16 of the fixed or stationary frame 10. The outer edge of the support plate 163 is supported on a transversely extending frame member 170, opposed ends of which are suitably secured, as by welding, to angularly disposed angle bars 171, 172. These angle bars 171, 172 extend downwardly and rearwardly at an angle and the lower ends thereof are welded to the transverse frame member 13 of the fixed frame 10.

One end of the reel 160 is defined by an internally toothed gear or ring gear 174 (Figures 1 and 2) which meshes with a pinion 175 fixedly mounted on one end of a stud shaft 176 which is rotatably mounted in the upper portion of the bearing stand 162. A relatively large spur gear 177 is also fixedly mounted on the stub shaft 176 and this spur gear 177 meshes with a pinion 180 fixedly mounted on another stub shaft 182 which is rotatably mounted in the lower portion of the bearing stand 162. This shaft 182 also has a sprocket wheel 184 fixedly mounted thereon on which a sprocket chain 185 is mounted. The sprocket chain 185 extends to the right in Figure 2 and is also mounted on a sprocket wheel 186 which is fixedly mounted on a motor shaft

187. The shaft 187 projects from a gear reduction reversing motor 190, which, as shown in Figure 8, has wires 191 to 194, inclusive, extending therefrom. This motor 190 is suitably secured to the upper surface of the support plate 163.

The ends of the wires 191, 192 (Figure 8) remote from the motor 190 are connected to respective contact members 196a, 196b of a double pole snap switch 196. The ends of the wires 193, 194 remote from the motor 190 are connected intermediate the ends of respective wires 200, 201. The wires 200, 201 are connected at one end thereof to respective contacts 196c, 196d of the switch 196 and the other ends thereof are connected to the respective lead wires 73, 72. The switch 196 is also provided with a manually rotatable bus bar 197, which is employed in the same manner as that described for the bus bars 66, 88 associated with the respective motors 52, 88, for controlling the direction of rotation of the shaft 187 extending from the gear reduction reversing motor 190.

It is thus seen that, upon rotation being imparted to the shaft 187 in a clockwise direction in Figure 2, the gears 174, 175 and 177 will rotate in a counter-clockwise direction which will take up on the cables 145 and 146 to thus raise the vertically movable frame or elevator 120. It is evident that the elevator 120 will be lowered upon rotation of the motor shaft 187 in the opposite direction.

The carriage 124 for the cutting mechanism comprises a pair of longitudinally spaced transverse axles 205, 206 which are bridged by a motor support plate 207 suitably secured to the lower surfaces of the axles 205, 206 as by bolts 210, 211, respectively. These bolts 210, 211 also serve to secure a pair of laterally spaced spacing bars or frame members 212, 213 to the lower surface of the motor support plate 207. The bolts 211 also serve to secure one end of bearing blocks 215, 216 to the lower surfaces of the respective bars 212, 213, these bearing blocks 215, 216 also being secured to the bars 212, 213 by screws 217.

Opposed ends of the axles 205, 206 have respective flanged wheels or rollers 220, 221 rotatably mounted thereon which are adapted to ride on the lower flanges of the I-beams 121, 122. Since considerable dust, sawdust and shavings may be thrown about by the cutting means, to be presently described, there is disposed adjacent diametrically opposed sides of each of the wheels 220, 221, the legs of substantially U-shaped cleaning bars 222, which are shown as being formed from strap material and which are secured, as by screws 223, to the lower surfaces of the axles 205, 206. It will be observed in Figure 6 that the legs of the substantially U-shaped cleaning bars 222 are disposed immediately adjacent the upper surfaces of the lower flanges of the I-beams 121, 122 to thus remove any accumulation of shavings and the like from the upper surfaces of the flanges of the I-beams 121, 122 with movement of the wheeled carriage 124 in either direction.

The cutter head indicated broadly at 225 comprises a transverse shaft 226 which is rotatably mounted in the bearing blocks 215, 216 (Figures 6 and 7) and on which a blade holding member 227 is fixedly mounted between the bearing blocks 215, 216. This blade holding member 227 is shown in Figure 7 as being substantially rectangular in cross-section and has a plurality of cutting blades 230 suitably secured thereto, as by screws 231. In this instance, the blades 230 are secured in suitable grooves in the four side sur-

faces of the cutting blade holder 227 and each of the blades projects substantially beyond the edge of the cutting blade holder 227 to which the adjacent leading blade 230 is secured.

5 The shaft 226 extends to the left in Figure 6 beyond the bearing block 216 and has a pulley 233 suitably secured thereto which is engaged by a flat belt 234. The belt 234 extends upwardly and engages a larger pulley 235 which is fixedly mounted on a motor shaft 236 projecting from an electric motor 237. The electric motor 237 has wires 240 and 241 (housed in a cable 290) extending therefrom (Figures 6 and 8). The wire 240 is connected to one side of a manually operable switch 245 to the other side of which a wire 246 is connected. The ends of the wires 246 and 241 remote from the switch 245 and the motor 237, respectively, are connected intermediate the ends of the lead wires 73, 72, respectively. It is evident that the switch 245 is closed in order to cause rotation of the cutter head 225.

Now, in order to move the wheeled carriage 124 along the I-beams 121, 122, the motor 237 has a bar 252 welded to the upper surface thereof, 25 to which opposed ends of a sprocket chain 253 are connected. The lower reach of the sprocket chain 253 extends in opposite directions from the bar 252 and passes half around sprocket wheels 254, 255. There is provided a channel-shaped 30 guide member 256 (Figure 7) which is suitably secured, as by welding, to the upper surface of the bar 252 and through which the upper reach of the sprocket chain 253 passes to thus prevent the upper reach thereof from engaging the lower reach of the sprocket chain 253. The sprocket wheel 255 is mounted for rotation between a pair of closely spaced angle clips 260 which are suitably secured, as by welding, to a transverse frame member 261, opposed ends of which are welded 40 to standards 262, which are shown in the form of vertically disposed angle bars. The angle bars 262 extend downwardly and are welded to the upper surfaces of the I-beam 121, 122.

These standards 262 are braced by angularly disposed angle bars 263, the upper ends of which are 45 welded to the upper ends of the corresponding standards 262 and the lower ends of which are welded to the upper surfaces of the I-beams 121, 122. The sprocket wheel 254 is fixedly mounted on a drive shaft 265 (Figures 1, 5 and 6) which is 50 rotatably mounted in bearing blocks 266 suitably secured, as by screws 267, to corresponding standards 270 which are also shown in the form of angle bars. The standards 270 extend downwardly and their lower ends are welded to the 55 upper surfaces of the I-beams 121, 122. These standards 270 are also braced by angularly disposed angle bars 271 which are welded at their upper ends to the corresponding standards 270 and which are welded at their lower ends to the corresponding I-beams 121, 122.

The drive shaft 265 extends outwardly beyond the vertical plane of the outer edge of the I-beam 121 and has a V-belt pulley 273 fixedly mounted thereon (Figure 6) on which a V-belt 274 is mounted. The V-belt 274 is also mounted on a pulley 275 which is fixed on a motor shaft 276 projecting from a gear reduction electric reversing motor 277. The motor 277 is suitably secured to the upper surface of a motor support plate 278 which extends inwardly in Figures 2 and 6 and is suitably secured, as by welding, to the lower surface of the frame member 121 of the elevator 120. The plate 278 is reenforced by gussets 279.

The gear reduction electric reversing motor 277

has wires 280 to 283, inclusive, extending therefrom (Figures 1, 2, 5, 6 and 8). The wires 280, 281 extend upwardly from the motor 277, in Figure 8, and are connected to respective contact members 285a, 285b of a double pole snap switch 285 which is also provided with a manually oscillatable bus bar 286. The snap switch 285 is also provided with a pair of spaced contact members 285c 5 285d to which respective wires 287, 288 are connected.

The ends of the wires 287, 288 remote from the switch 285 are connected to the lead wires 73, 72, respectively. The ends of the wires 282, 283 remote from the motor 277 are connected intermediate the ends of respective wires 287, 288. 15 The direction of rotation of the shaft 276 extending from the gear reduction motor 277 is controlled by the bus bar 286 in the identical manner in which the motors 52, 80, 190 and 237 are controlled and a further description of its operation is therefore deemed unnecessary.

It is evident that, upon rotation being imparted to the shaft 276 in one direction, the shaft 265 may rotate in a clockwise direction to cause the lower reach of the sprocket chain 253 to move from right to left in Figures 1 and 7 to thus feed the cutter head 225 into the workpiece W as indicated in Figure 1, and, upon the cutter head 225 having moved beyond the left-hand or rear end of the workpiece W in Figure 1, the direction of rotation of the shaft 276 may then be reversed to cause the wheeled carriage 124 with the cutter head 225 to move from left to right in Figure 1 to where the cutter head will be disposed to the right of the right-handed end of the workpiece W.

A step in rotation is then imparted to the workpiece W for the desired distance and in the desired direction by manipulation of the bus bar 88 on the switch 87, which controls the motor 80 40 for rotating the traction wheels 104 and 105 in the desired direction. Since the electric motor 237 on the wheeled carriage 124 must move to and fro on the vertically movable frame 120 it is preferred that the cable 290, which extends from the electric motor 237 and which houses the wires 240 and 241, be made flexible.

The cable 290 is shown in Figure 1 as extending upwardly and being suitably secured to the horizontally disposed channel bar 154 after which the cable 290 extends downwardly into a junction box 291. The junction box 291 may house the master switch 76 and may also serve as a point to which all of the wires from the various motors 52, 80, 190, 237 and 277 may extend, after which the wires from these last-named motors may extend through a cable 292 downwardly to be connected to the respective switches 65, 87, 196, 245 and 285. The junction box 291 and the cables 290 and 292 have been omitted from the schematic drawing in Figure 8 for purposes of clarity since it is a matter of choice as to the exact manner in which the wires from the respective motors 52, 80, 190, 237 and 277 may be connected to the corresponding switches.

It will be observed in Figures 1, 2 and 5 that the switches 65, 87, 196, 245 and 285 are suitably secured to the upper surface of a switch supporting plate 295 which is suitably secured, as by welding, to the upper surface of the transverse frame member or angle bar 165. These switches 65, 87, 196, 245 and 285 may be of any desired construction and are shown in the drawings as being of a type, each having a lever associated therewith for manipulation by an operator for

controlling the position of the corresponding bus bars 66, 88, 197 and 286 and the switch 245 for controlling operation of the respective motors 52, 80, 190, 277 and 237.

It is thus seen that I have provided an improved machine for removing stock from the surface of a substantially cylindrically-shaped workpiece which may be of substantially the same diameter throughout its length or which may be smaller at one end than at the other end and wherein the entire operation of the machine may be controlled by a single operator. For example, the operator may first position the log or workpiece W on the traction wheels 104 to 107, inclusive, of the log supporting frame 27 substantially as shown in Figures 1, 2 and 6 after having raised the elevator or vertically movable frame 120 by manipulation of the bus bar 197 (Figure 8) associated with the switch 196 (Figures 5 and 8).

After the log or workpiece W is positioned in the manner heretofore described, the elevator may be lowered by reversing the motor 190 in the manner heretofore described to determine the desired depth of cut to be made in the workpiece by the cutter head 225. It is to be assumed that the wheeled carriage 124 with the cutter head 225 is then disposed to the right of the right-hand end of the workpiece W in Figure 1, and the operator then starts the motor 237 by manipulation of the switch 245 to thereby cause the cutter head 225 to rotate in a clockwise direction in Figures 1 and 7.

It is evident that in the event of the workpiece W being of smaller diameter at one end thereof than it is at the other end thereof, the switch 65 will then be manipulated by an operator to cause rotation of the threaded shaft 50 (Figure 2) in the desired direction for either raising or lowering the corresponding end of the tiltable frame 27 until the upper surface of the workpiece W extends in a plane substantially parallel to that of the path of travel of the carriage 124. The motor 52 would then be stopped as well as the motor 190, and the operator would then energize the motor 277 by manipulation of the switch 285 to cause the shaft 265 to rotate in a clockwise direction in Figure 1. The sprocket chain 253 would then move the carriage 124 from right to left or rearwardly in Figures 1, 5 and 7 and the cutter head 225 would then remove stock from the uppermost portion of the workpiece W.

Upon the carriage 124 reaching the end of its stroke in a rearward direction, the operator would again manipulate the switch 285 to cause the shaft 265 to rotate in the opposite direction and to again return the carriage 124 with the cutter head 225 to its position adjacent the right-hand end of the workpiece W in Figure 1.

The operator would then manipulate the switch 87 to rotate the workpiece W in either direction for the desired distance so that a subsequent cut made by the cutter head 225 would remove stock from the upper surface of the workpiece W immediately adjacent the point at which stock has previously been removed therefrom. The workpiece rotating operation and the rearward and forward strokes of the carriage 124 would then be alternately repeated until the bark or some of the stock has been removed from the entire periphery of the workpiece W.

The elevator 120 would then be raised and the switches 65, 87, 196, 245 and 285 moved to opened position as shown in Figure 8, after which the workpiece W could be removed from the traction wheels 104 to 107, inclusive, by suitable grapping

hooks or other devices in the hands of the operator and replaced by another log or workpiece W to complete a cycle in the operation of the machine.

In the drawings and specification, there has been set forth a preferred embodiment of the invention and although specific terms are employed, they are used in a generic and descriptive sense only and not for purposes of limitation, the scope of the invention being defined in the claims.

I claim:

1. Apparatus for removing stock from the upper surface of a workpiece comprising an elongated support for the workpiece, means for pivotally mounting the support for the workpiece at a point substantially midway between its ends, means connected to one end of the support for swinging the support on its pivot, a vertically movable frame spaced above the support, a driven rotatable cutting means carried by the vertically movable frame, means for raising and lowering the vertically movable frame so as to position the cutting means for removing the desired depth of stock from the upper surface of the workpiece and means for moving the cutting means longitudinally of the workpiece for removing the stock therefrom.

2. Apparatus for removing stock from the upper surface of a workpiece comprising an elongated support for the workpiece, means for pivotally mounting the support for the workpiece at a point substantially midway between its ends, means connected to one end of the support for swinging the support on its pivot, a vertically movable frame spaced above the support, a driven rotatable cutting means carried by the vertically movable frame, means for raising and lowering the vertically movable frame so as to position the cutting means for removing the desired depth of stock from the upper surface of the workpiece, means for moving the cutting means longitudinally of the workpiece for removing the stock therefrom, and means for rotating the workpiece following each operation of the cutting means to thus present a different portion of the workpiece to the cutting means for each successive cutting operation.

3. Apparatus for removing stock from the periphery of a substantially cylindrically-shaped workpiece, such as logs and the like, comprising an elongated supporting frame for the workpiece, means for pivotally mounting the supporting frame intermediate its ends, means connected to one end of the supporting frame for swinging the supporting frame on its pivot, a vertically movable frame spaced above the support, a driven rotatable cutting means carried by the vertically movable frame, means for raising and lowering the vertically movable frame so as to position the cutting means for removing the desired amount of stock from the upper surface of the workpiece, means for reciprocatorily moving the cutting means longitudinally of the workpiece for removing the stock therefrom and means for rotating the workpiece any predetermined distance following each cutting operation to thus present a different portion of the workpiece to the cutting means for each subsequent cutting operation.

4. Apparatus for removing stock from the periphery of a substantially cylindrically-shaped workpiece, such as logs and the like, comprising a supporting frame for the workpiece, means for pivotally mounting the supporting frame intermediate its ends, means connected to one end of the supporting frame for swinging the sup-

porting frame on its pivot, a vertically movable frame spaced above the support, a driven rotatable cutting means carried by the vertically movable frame, manually controlled electrically operable means for raising and lowering the vertically movable frame so as to position the cutting means for removing the desired amount of stock from the upper surface of the workpiece, manually controlled electrically operable means for reciprocatorily moving the cutting means longitudinally of the workpiece for removing the stock therefrom and manually controlled electrically operable means for rotating the workpiece a predetermined distance following each cutting operation to thus present a different portion of the workpiece to the cutting means for each subsequent cutting operation.

5. Apparatus for removing stock from the periphery of a substantially cylindrically-shaped workpiece, such as a log and the like, comprising a supporting frame for the workpiece, means pivotally mounting the supporting frame intermediate its ends, a vertically movable frame spaced above the support for the workpiece and beneath which the workpiece is to be disposed when it is resting upon the support therefor, driven rotatable cutting means carried by the vertically movable frame, means for raising and lowering the vertically movable frame so as to position the cutting means for removing the desired amount of stock from the upper surface of the workpiece, means for moving the cutting means longitudinally of the workpiece for removing the stock therefrom, means for rotating the workpiece any predetermined distance following each cutting operation to thus present a different portion of the workpiece to the cutting means for each subsequent cutting operation, and means for tilting the frame for supporting the workpiece to simultaneously raise one end and to lower the other end of the workpiece to thereby position the upper surface of the workpiece in substantially parallel relation to the path of travel of the cutting means in the event of the workpiece being of smaller diameter at one end than at the other end.

6. Apparatus for removing stock from the periphery of a substantially cylindrically-shaped workpiece such as a log and the like comprising a support for the workpiece, a vertically movable frame spaced above the support for the workpiece and beneath which the workpiece is to be disposed when it is resting upon the support therefor, driven rotatable cutting means carried by the vertically movable frame, manually controlled electrically operable means for raising and lowering the vertically movable frame so as to position the cutting means for removing the desired amount of stock from the upper surface of the workpiece, manually controlled electrically operable means for moving the cutting means longitudinally of the workpiece for removing the stock therefrom, manually controlled electrically operable means for partially rotating the workpiece following each cutting operation to thus present a different portion of the workpiece to the cutting means for each subsequent cutting operation and manually controlled electrically operable means for tilting the means for supporting the workpiece to thereby position the upper surface of the workpiece in substantially parallel relation to the path of travel of the cutting means in the event of the workpiece being of smaller diameter at one end than at the other end.

7. A machine for removing stock from the periphery of a substantially cylindrically-shaped workpiece comprising a fixed frame, a tilttable workpiece supporting frame oscillatably mounted on the fixed frame on a transverse pivot disposed substantially midway its ends, radially and longitudinally spaced rotatable means carried by the tilttable frame and on which the workpiece is to be disposed during the removal of stock therefrom, manually controlled means for imparting rotation to the spaced rotatable means to thereby impart rotation to the workpiece, a vertically movable frame spaced above the tilttable frame, manually controlled means for raising and lowering the vertically movable frame, a wheeled carriage carried by the vertically movable frame, a cutter head rotatably mounted on and depending from the wheeled carriage, manually controlled means for imparting rotation to the cutter head, manually controlled means for imparting reciprocatory horizontal movement to said carriage, whereby said vertically movable frame may be positioned to thereby position the cutter head for cutting the required depth of stock from the upper surface of the workpiece and said carriage may be moved parallel to the upper surface of the workpiece for removing stock therefrom and whereby said workpiece may be partially rotated between horizontal movements of the wheeled carriage to present a different portion of the workpiece to the cutter head for removing stock therefrom, and means for swinging the workpiece supporting frame on its pivot to simultaneously raise one end and lower the other end to position the upper edge of the workpiece in a plane parallel to the path of travel of cutter head.

8. Apparatus for removing stock from the upper surface of a substantially cylindrically-shaped workpiece which may be tapered throughout its length, such as logs and the like, comprising a tilttable support for the workpiece including an elongated frame pivotally supported at its middle point, a pair of transversely spaced longitudinally extending shafts rotatably supported by the frame, at least two longitudinally spaced traction wheels fixed on each of the longitudinally extending shafts and forming a cradle for said workpiece manually controlled mechanically operable means for imparting rotation to at least one of said shafts for selected amounts to, in turn, impart rotation to the workpiece for selected amounts, manually controlled mechanically operable means for moving the elongated frame on its pivot for simultaneously raising and lowering the opposed ends of the elongated frame, a driven rotatable cutting means spaced above the elongated frame and means for moving the cutting means longitudinally of the workpiece for removing stock therefrom whereby, upon said workpiece being of smaller diameter at one end than at its other end, the position of the tilttable table may be varied to position the uppermost surface of the workpiece in parallel relation to the path of travel of the cutting means to facilitate the removal of stock from the upper surface of the workpiece for its entire length and whereby the workpiece may be rotated any predetermined amount following each cutting operation to present a different portion of the workpiece to the cutting means.

9. A machine for removing stock from the periphery of a substantially cylindrically-shaped workpiece comprising a fixed frame, a support

carried by the fixed frame for supporting a workpiece, means carried by the workpiece supporting frame for partially rotating the workpiece, a vertically movable frame spaced above the support for the workpiece, manually controlled means for raising and lowering the vertically movable frame, a wheeled carriage carried by the vertically movable frame and mounted for horizontal movement longitudinally of the vertically movable frame and substantially parallel to the axis of the workpiece, a driven cutter head rotatably mounted on and depending from the wheeled carriage, means for imparting horizontal movement to said carriage comprising a first sprocket wheel disposed adjacent one end of said vertically movable frame and being rotatably mounted thereon, a second sprocket wheel disposed adjacent the end of the vertically movable frame remote from the end adjacent which the first sprocket wheel is disposed, a transverse shaft rotatably mounted on the vertically movable frame and on which the second sprocket wheel is fixedly mounted, a sprocket chain mounted on and extending between the first and second sprocket wheels, a connection between one of the reaches of said sprocket chain and the wheeled carriage and manually controlled electrically operable means for imparting rotation to the shaft in either direction whereby, said vertically movable frame may be positioned to thereby position the cutter head for cutting the required depth of the stock from the upper surface of the workpiece and said carriage may be moved parallel to the upper surface of the workpiece for removing stock therefrom upon movement of the carriage in one direction and whereby said carriage with its cutter head may be returned to its original position so as to permit the workpiece to be partially rotated to present a different portion of the workpiece to the cutter head for removing stock therefrom.

10. A machine for removing stock from the periphery of a substantially cylindrically-shaped workpiece comprising a fixed frame, a tilttable workpiece supporting frame oscillatably mounted on the fixed frame, means carried by the tilttable workpiece supporting frame for partially rotating the workpiece, a shifttable frame vertically movable between the tilttable frame and a top portion of the fixed frame, manually controlled means for raising and lowering the vertically movable frame comprising cables connected to opposed ends of the vertically movable frame, pulleys carried by the fixed frame and spaced above the vertically movable frame and over which and from whence said cables pass to a point at one end of the machine, a reel rotatably mounted on the fixed frame and to which said cables are secured, a reversing motor carried by the fixed frame, mechanical connections between the reversing motor and said reel for imparting rotation to the reel in either direction and manually controlled means for controlling the motor so as to control the direction of rotation of the reel whereby, upon rotation of said reel in one direction the elevator will be raised and, upon rotation of said reel in the opposite direction, the elevator will be lowered, a wheeled carriage carried by the vertically movable frame, a cutter head rotatably mounted on and depending from the wheeled carriage, means for imparting rotation to the cutter head and manually controlled means for imparting horizontal movement to said carriage whereby said vertically movable

frame may be positioned to thereby position the cutter head for cutting the required depth of stock from the upper surface of the workpiece and said carriage may be moved parallel to the upper surface of the workpiece for removing stock therefrom and also whereby said workpiece may be partially rotated between horizontal movements of the wheeled carriage to present a different portion of the workpiece to the cutter head.
